(57) **CLAIM**

We claim the ornamental design for a dosing assembly, as shown and described.

DESCRIPTION

FIG. 1 is a side view of a dosing assembly showing our new design;

FIG. 2 is a front view thereof;

FIG. 3 is the opposite side view thereof;

FIG. 4 is a rear view thereof; and,

FIG. 5 is a top view thereof.

The present application is directed to the shape and contour of a dosing assembly and/or a dosing head of the design illustrated in the drawings. Other features of the drawings shown in broken lines are not considered part of the claimed subject-matter.
